(57) CLAIM

The ornamental design for an inflatable snow tube, as shown and described.

DESCRIPTION

FIG. 1 is a perspective view of the inflatable snow tube showing my new design;

FIG. 2 is a top plan view thereof;

FIG. 3 is a bottom plan view thereof;

FIG. 4 is a right side elevational view, the left side view being a mirror image thereof;

FIG. 5 is a front elevational view thereof; and,

FIG. 6 is a rear elevational view thereof.

The broken line showing of a rope handle in FIG. 1 is for illustrative purposes only and forms no part of the claimed design.
